UNITED STATES PATENT OFFICE.

JOHN F. O'CONNOR, OF CHICAGO, ILLINOIS, ASSIGNOR TO WILLIAM H. MINER, OF CHICAGO, ILLINOIS.

DRAFT-RIGGING FOR RAILWAY-CARS.

1,128,354.

Specification of Letters Patent. Patented Feb. 16, 1915.

Application filed October 9, 1913. Serial No. 794,213.

To all whom it may concern:

Be it known that I, JOHN F. O'CONNOR, a citizen of the United States, residing at Chicago, in the county of Cook and State of Illinois, have invented a certain new and useful Improvement in Draft-Rigging for Railway-Cars, of which the following is a full, clear, concise, and exact description, reference being had to the accompanying drawings, forming a part of this specification.

My invention relates to improvements in draft rigging for railway cars.

The object of my invention is to provide a draft rigging of the tandem variety of strong construction and efficient operation, and one in which the draft members are securely bound together at the point of attachment of the draft rigging thereto.

In the drawings forming a part of this specification—Figure 1 is a side elevation partly in vertical longitudinal sections on line 1—1 of Fig. 2 of a draft rigging embodying my invention; Fig. 2 is a plan view partly in horizontal section on line 2—2 of Fig. 1; Fig. 3 is a cross section taken on line 3—3 of Fig. 1; Fig. 4 is a cross section taken on line 4—4 of Fig. 1; Fig. 5 is a detailed view showing in elevation one of the cheek plates; Fig. 6 is a plan view of a frame; Fig. 7 is a plan view of one of the draft plates; Figs. 8, 9 and 10 illustrate a modification, Fig. 8 being a side elevation partly in vertical longitudinal section taken on line 8—8 of Fig. 9, Fig. 9 a plan view partly in horizontal section on line 9—9 of Fig. 8, and Fig. 10 an enlarged detail showing in perspective one of the followers.

In the drawings the numerals 11, 11 represent draft sills or parts of the car frame to which the draft rigging is applied. The draft sills, the end sill 12, the buffer block 13, the draw-bar carry iron 14, the draw bar 15 and the yoke 16 secured to the draw-

bar are all parts of well known construction, and need no further description.

The cheek plates 17, 17 are oppositely arranged between the draft members, and are secured to said draft members by suitable means, preferably the rivets 18, 18. The

cheek plates are adapted to interengage with a frame 19, hereinafter described, in preferable construction each of the cheek plates being provided with a plurality, preferably two female dove-tailing mortises 55 20, 20 to receive the flanges 21, 21 of the frame 19. Each of the said mortises 20 preferably has a narrowed lateral opening, and each is open underneath to permit the insertion from below of the flanges 21 of 60 the frame 19 in assembling the frame with the other parts of the draft rigging.

The frame 19 comprises a central connecting block-like member 22 having a vertical longitudinally extended slot 23 therein, a front connecting cross member 24 and a rear connecting cross member 25. The sides of the frame are formed by the flanges 21, there being a pair of flanges connecting the front cross member 24 with the 70 intermediate cross member 22, and another pair connecting the intermediate cross member 22 with the rear cross member 25, thus forming a front opening or pocket 26 and a rear opening or pocket 27. Each of 75 the flanges 21 dove-tails in an adjacent mortise 20 hereinbefore described, in preferable construction each of said flanges being splayed and forming a male-dove-tailing flange. Each side of the intermediate 80 cross member 22 of the frame 19 interengages with a portion of the adjacent cheek plate, in preferable construction each cheek plate having an intermediate splayed flange 85 28 forming a male member adapted to enter a mortise 29 in the adjacent side of the intermediate connecting member 19 forming the female dove-tailing member.

The frame 19 is adapted to be mounted within the yoke 16, within which there is 90 also mounted a pair of plates 30, 30. The ends of the plates engage against the front and rear walls of the lateral opening 31 of the draft yoke 16, that is, in the particular construction shown in the drawings the 95 front ends of said plates engage against the rear face 32 of the draw bar 15, and the rear ends of said plates engage against the forward face 33 of the filler block 34 at the rear end of the yoke. In preferable arrange- 100

ment the said plates 30 are arranged one above the other, each having a forward in-turned lug 35 forming a shoulder 36 at its rear face, central in-turned lugs 37 forming front intermediate shoulders 38 and rear intermediate shoulders 39, and rear in-turned lugs 40 forming rear shoulders 41, thus forming a front opening or pocket 42 between the front and intermediate shoulders, and a rear opening or pocket 43 between the rear and intermediate shoulders. In preferable construction each of said plates is provided intermediate its ends and on the outer face of the intermediate lug 37 with a recess 44, one of said recesses to receive the head 45 and the other of said recesses to receive the nut 46 of the bolt 47, which passes through a transverse perforation 48 in each of the plates, and also through the perforation 23 in the intermediate cross member of the frame to assist in holding said plates together. The upper plate 30 is arranged between the upper faces of the cross members of the frame and the upper limb 49 of the yoke 16. The lower plate 30 is arranged between the lower faces of the cross members of the frame and the lower limb 50 of the yoke 16. The vertical depth of the flanges 21 of the frame is in preferable construction greater than the vertical depth of the cross members connecting the same.

In normal position of the parts of the draft rigging the front and front intermediate shoulders 36 and 38 respectively of the plates 30 substantially register with the rear face of the front connecting member 24 and the forward face of the intermediate connecting member 22 of the frame 19, and the rear intermediate shoulders 39 and the rear shoulders 41 respectively of the plates 30 substantially register with the rear face of the intermediate cross member 22 and the front face of the rear cross member 25 respectively of the frame 19. In the substantially registering front pockets of the plates 30 and frame 19 is mounted a compression resisting member consisting preferably of an outer spring 51 and an inner spring 52 nested therein. In the substantially registering rear pockets of the plates 30 and the frame 19 is mounted a compression resisting member consisting preferably of an outer spring 53 and an inner spring 54 nested therein. Front and rear tie plates 55 and 56 respectively are suitably secured to the draft members, preferably by the bolts 57. In preferable construction the inner face of each of the plates 30 between the in-turned lugs thereof is shaped to conform to the contour of the springs, as illustrated at the numerals 58, 58 in Fig. 3 of the drawings.

It will be observed that the frame 19 serves to securely tie the draft members together through the interengagement and connection with the cheek plates extended

from the draft members. The longitudinal dimension of each of the front lugs 35 of the plates 30 is greater than the longitudinal dimension of the front cross member 24 of the frame 19, leaving a suitable space 59 between the front cross member 24 of the frame 19 and the rear face of the draw bar to permit the rearward movement of the draw bar and the plates 30. The longitudinal dimension of the rear lugs 40 of the plates 30 is greater than the longitudinal dimension of the rear cross member 25 of the frame 19 to permit the forward movement of the draw bar and of the plates 30.

On forward movement of the draw bar 30 the front set of springs is stopped at the forward end against the front cross member 24 of the frame 19, the rear ends of the springs being in engagement against the front intermediate shoulders 38 of the plates 30, which in the forward movement of the plates compress the front springs. The rear set of springs forwardly engages against the rear face of the intermediate cross member 22 of the frame 19, and rearwardly is in engagement with the rear shoulders of the plates 30, which in the forward movement of the plates compress the rear springs. The bolt 47 moves forwardly within the slot 23 in the intermediate cross member 22 of the frame 19. On rearward movement of the draw bar the front set of springs is in engagement against the front face of the intermediate cross member 22 of the frame 19, and is forwardly engaged by the front shoulders 36 of the plates 30, which in the rearward movement of said plates with the draw bar and yoke rearwardly compresses the front set of springs. The rear set of springs is rearwardly in engagement against the rear cross member 25 of the frame 19, and is forwardly engaged against the rear intermediate shoulders 39 of the plates 30, which in the rearward movement of the plates 30 rearwardly compress the rear springs.

In the modification illustrated in Figs. 8 to 10 inclusive of the drawings 60, 60 represent draft sills or parts of the car frame to which the draft rigging is applied, 61 the end sill, 62 a buffer block, 63 the draw bar carry iron, 64, 64 tie plates, 65 the draw bar, and 66 the draft yoke secured to the draw bar. Oppositely arranged between the draft members 60 and secured thereto are the cheek plates 67, 67 provided with front stop shoulders 68, 68, middle stop shoulders 69, 69, rear stop shoulders 70, 70, front limiting stop shoulders 71, 71 and rear limiting stop shoulders 72, 72. A frame 73 inter engages with the middle shoulders 69 of the cheek plates, and serves through said cheek plates to tie the draft members together. The said frame consists of a block like member provided on either side with mortise 74 forming a female member dove

tailing with the middle shoulder 69, which is splayed in preferable construction, and forms the male member for the mortise 74. In assembling the frame 73 with the cheek 5 plates the same is lifted into engagement from underneath with the other parts of the draft rigging included within the yoke 66. The numeral 75 represents the front follower and 76 the rear follower. The member 10 73 and the followers are of substantially the same vertical dimensions, and are suitably narrow to permit the insertion between their upper faces and the upper limb 77 of the draft yoke of the upper plate 78 hereinafter described, and also to permit the insertion between them and the lower limb 20 79 of the draft yoke of the lower plate 80. The said plates 78 and 80 are each provided with inturned front lugs 81, intermediate lugs 82 and rear lugs 83, the front lugs forming front shoulders 84, the intermediate lugs forming front intermediate shoulders 85 and rear intermediate shoulders 86, the rear lugs 83 forming rear shoulders 87. 25 A bolt 89 passing through each of the plates 78 and 80 serves to assist in holding said plates together, said bolt being provided with a head 90 received within a recess 91 in the upper plate 78, and a nut 92 received within a recess 93 in the lower plate 80. Said bolt passes through a vertical slot 94 in the frame 73, said slot being longitudinally extended to permit the movement of the bolt therein in the reciprocating movements of the plates 78 and 80. Within the 30 front pocket 95 formed between the front and intermediate inturned lugs of the plates and between the front follower and the frame 73 is mounted a compression resisting member consisting preferably of an outer spring 96 and an inner spring 97 nested therein. Within the rear pocket 98 formed between the intermediate inturned lugs of the plates 78 and 80 and the rear lugs 83 35 thereof, and between the frame 73 and the rear follower 76 is disposed a rear compression resisting member consisting preferably of an outer spring 99 and an inner spring 100 nested therein. 40 In view of the description of the operation of the preferred form of my invention illustrated in Figs. 1 to 7 inclusive of the drawings the operation of the modified form illustrated in Figs. 8 to 10 inclusive will 45 be readily understood. On forward movement of the draw bar the front springs are stopped by the front follower 75, and are compressed against the same through their rearward engagement with the front intermediate shoulders 85, 85 of the plates 78 and 80, and the rear springs are stopped against the frame 73, and are compressed there against through their rearward engagement with the rear shoulders 87, 87 of the 50 plates and the rear follower 76. On rear- ward movement of the draw bar the front springs are stopped against the frame 73, and are compressed against the same through their forward engagement against the front shoulders 84, 84 of the plates and 55 the front follower 75. The rear springs are stopped against the rear follower 76, and are compressed against the same through their engagement with the rear intermediate shoulders 86, 86 of the plates. 75

I claim:

1. In a draft rigging for railway cars, in combination, a draw bar, a yoke secured thereto, draft members, cheek plates secured to the draft members, tandem arranged 80 springs, spring stops, a bolt and means for actuating the springs, the spring stops comprising a frame having spaced apart front, rear and intermediate cross members, the sides of said frame being provided between 85 each end cross member and the intermediate cross member with a splayed male dove-tailing flange, the cheek plates being provided with a plurality of female dove-tailing mortises to receive the flanges of the frame, said 90 mortises being open underneath to permit the insertion of the male flanges therein, the intermediate cross member having a longitudinally extended opening, the means for actuating the springs comprising a pair of 95 plates, said plates being oppositely arranged within the yoke and movable therewith, each of said plates having inwardly projecting front, rear and intermediate shoulders, one set of springs being seated between the front 100 and intermediate shoulders, the other set being seated between the rear and intermediate shoulders of said plates, a bolt connecting said plates, said bolt passing through the opening in the intermediate cross member 105 of the frame, and being slidable therein.
2. In a draft rigging for railway cars, in combination, a draw bar, a yoke secured thereto, draft members, cheek plates secured to the draft members, tandem arranged 110 springs, spring stops and means for actuating the springs, the spring stops comprising a frame having spaced apart front, rear and intermediate cross members, the sides of said frame being provided between each end cross 115 member and the intermediate cross member with a splayed male dove-tailing flange, the cheek plates being provided with a plurality of female dove-tailing mortises to receive the flanges of the frame, said mortises being open 120 underneath to permit the insertion of the male flanges therein.
3. In a draft rigging for railway cars, in combination, draft members, cheek plates secured to the draft members, a frame mounted between the cheek plates and provided with a slot, said frame having front, rear and intermediate cross arms forming stops for tandem arranged 125 springs, said frame and cheek plates having cooperating inter-engag- 130

22
ing tongues and grooves, a draw-bar, a yoke encircling said frame and connected to the draw-bar, tandem arranged springs, and means for compressing the springs upon movement of the draw-bar and yoke, said means including plates mounted within the yoke and on opposite sides of said frame and a bolt connecting said plates, said bolt being longitudinally slidable in the slot in said frame.
